UNITED STATES PATENT OFFICE.

ELMER R. COE, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING SYSTEM.

1,324,230.

Specification of Letters Patent.

Patented Dec. 9, 1919.

Original application filed September 12, 1917, Serial No. 190,942. Divided and this application filed April 11, 1919. Serial No. 289,451.

To all whom it may concern:

Be it known that I, ELMER R. COE, a citizen of the United States, residing at Wilkinsburg, in the county of Allegheny and State of Pennsylvania, have invented certain new and useful Improvements in Railway Signaling Systems, of which the following is a specification.

My invention relates to railway signaling systems, and particularly to systems of the type comprising alternating current track circuits for the control of signals.

The present application is a division of my copending application filed September 12, 1917, Serial No. 190,942, for an improvement in relays.

I will describe one form of signaling system embodying my invention, and will then point out the novel features thereof in claims.

In the accompanying drawings, Figure 1 is a diagrammatic view showing one form of signaling system embodying my invention. Fig. 2 is a view showing in vertical section the construction of a relay which is illustrated diagrammatically in Fig. 1. Fig. 3 is a sectional view on the line III—III of Fig. 2, looking in the direction indicated by the arrows. Fig. 4 is a sectional view on the plane indicated by the line IV—IV in Fig. 2 looking in the direction of the arrows. Figs. 5 and 6 are sectional views taken on the planes indicated by the lines V—V and VI—VI, respectively, in Fig. 1, and looking in the direction indicated by the arrows.

Similar reference characters refer to similar parts in each of the several views.

Referring first to Fig. 2, the relay, which is designated as a whole by the reference character R, is inclosed in a box comprising a base plate 1, a top plate 2, and glass sides 3.

The relay comprises a motor M which, as here shown, is of the induction type, comprising a rotor 4 and two stator windings 5 and 6. For simplicity of illustration this motor is shown diagrammatically in Fig. 2, but it is understood that in practice the motor will be mounted on the base plate 1. The motor M is free to rotate in each direction, and as is well understood, the direction of rotation depends on the relative instan-

taneous phases of the alternating currents supplied to the stator windings 5 and 6. 55

A and B are two centrifuges which are operatively connected with the motor M in such manner that one centrifuge or the other will be operated according as the motor rotates in one direction or the other. The 60 mechanism between the motor and the centrifuge is as follows:

Operatively connected with the rotor of motor M is a gear wheel 7 mounted on a spindle 15 which rotates in ball-bearings 16 and 16^a mounted in a tubular projection 1^b integral with the base plate. This wheel 7 meshes with two gears 8 and 9, which are connected with the centrifuge A and B, respectively, through directional clutches. 70 Considering centrifuge A particularly, the main spindle 12 thereof extends downwardly and rotates in ball-bearings 13 and 13^a mounted in a tubular projection 1^a integral with the base plate. The gear 8 is provided 75 with a hub 8^a by which this gear is mounted to rotate in ball-bearings 14 and 14^a which are carried by spindle 12 and are held in place on the spindle by a stop 17 fixed to the spindle. The directional clutch (see 80 also Fig. 3) is formed by the gear 8, a block 10 fixed to the spindle and having triangular notches 10^a cut therein, and balls 11 located in these notches and operating between the block 10 and the gear 8. When the gear 8 rotates in the direction indicated by the arrow in Fig. 3 it drives centrifuge A in the same direction, but when the gear rotates in the other direction the balls 11 do not wedge and so the centrifuge remains 85 at rest.

The mechanism between gear 9 and centrifuge B is exactly the same as that between gear 8 and centrifuge A, the directional clutch (see Fig. 4) in this instance 95 being so arranged that the centrifuge is operated when gear 9 rotates in the direction of the arrow in Fig. 3 but not in the other direction.

It will be seen from the foregoing that 100 when motor M rotates in one direction it operates centrifuge A, and that when it rotates in the other direction it operates centrifuge B.

Centrifuge A controls a contact 18—19, and 105 centrifuge B controls a contact 20—21, the

mechanism being as follows: Referring to centrifuge A, the spindle is provided at its upper end with two diametrically disposed arms 22 and 22^a in which are journaled the 5 centrifuge cranks 23 and 23^a which are provided as usual with fly-balls 25. The inner ends of these cranks project into holes in a head 24 which is fixed to a spindle 26 arranged to be guided by, and to slide freely 10 in the hollow spindle 12. The upper end of this head rotates on a ball-bearing 28 carried by a link 27. It will be seen that head 24, and consequently the link 27, are moved up and down according as the centrifuge 15 balls 25 move out and in, that is, according as the centrifuge is rotating or is at rest. Link 27 is pivotally connected at its upper end to a contact carrying block 29 which is pivotally mounted at point 29^a by means not 20 shown in the drawing. This block carries contact finger 18. When the centrifuge A is at rest, block 29 occupies the position shown, so that contact 18-19 is open; but when the centrifuge is rotated at or above 25 a given speed, block 29 is swung in clockwise direction about its pivotal point so that the contact becomes closed.

The control of contact 20-21 by centrifuge B is the same as that of contact 18-19 30 by centrifuge A.

It follows from the foregoing that contact 18-19 or contact 20-21 is closed according as motor M rotates in one direction or the other, provided, however, that the speed of 35 rotation of this motor is at or above a predetermined value.

As a safeguard against false operation of the relay means are preferably provided to prevent rotation of each centrifuge A and B 40 in the direction opposite to that in which it is positively driven by motor M. As here shown, this is accomplished by providing the head 24 with ratchet teeth 33 (see Figs. 2, 5 and 6) which coact with a pawl 32 attached 45 to the contact block 29. The pawl is in the path of the ratchet teeth only when the block is in the position wherein the contact is open, that is, when the centrifuge is at rest, so that the device is noiseless when the 50 centrifuge is operating. As will be clear from Figs. 5 and 6, each pawl and ratchet device permits the corresponding centrifuge to rotate in the direction in which it is driven by the motor, but prevents rotation 55 of the centrifuge in the opposite direction.

I also preferably provide means for interlocking the two contact blocks 29 so that both contacts 18-19 and 20-21 cannot be closed at the same time. This means, as here 60 shown, comprises a bar 48 pivotally connected at its opposite ends with the brackets supporting the contact blocks 29. One of these pivotal connections includes a slot 49 in the bar 48. The distance between the pivotal points in this bar, and the length of the

slot 49, are such that both contacts may be fully opened simultaneously, but that when either contact is closed the bar will prevent the other contact being closed at the same time. 70

Leaving for the moment the structure of the relay, I will refer to Fig. 1 and explain the operation, in the signaling system, of the parts of the relay thus far described.

In Fig. 1, the reference character 34 designates the track rails of a railway, which rails are divided by insulated joints 75 to form a track section C-D. Located adjacent the exit end of this track section is a 75 source of alternating current, which, as here shown, is a transformer 30, the secondary of which is connected with the track rails and the primary of which is connected with transmission mains 60 to which signaling current is supplied from a generator G. 80 This source may be reversibly connected with the track rails by a pole-changer P, which pole-changer, as here shown, is operated by a signal S' for the track section next in advance. Located adjacent the entrance 85 end of section C-D is a signal S, which is controlled by the relay R shown in Fig. 2. One stator winding 5 of this relay is connected directly with the track rails of section C-D, this connection including a winding 35 of an auxiliary relay E, the function of which is hereinafter explained. The other stator winding 6 is constantly supplied with alternating signaling current from the secondary of a transformer 31, the primary of which is connected with the transmission mains 60. Signal S is adapted 90 to give three indications, namely, "stop," "caution" and "proceed." This signal is provided with a caution circuit which is controlled by contact 18-19 and with a proceed circuit which is controlled by contact 20-21. The caution circuit is from the secondary of transformer 31 through wires 41 and 42, contact 19-18, wire 43, mechanism 95 of signal S, and wires 44 and 45 to transformer 31. The proceed circuit is from the secondary of transformer 31, through wires 41, 42 and 46, contact 20-21, wire 47, mechanism of signal S and wires 44 and 45 100 to transformer 31. 105

It will be seen from the foregoing that when the track section C-D is occupied by a car or train W, as shown in the drawing, motor M of relay R is deenergized so that 110 both contacts 18-19 and 20-21 are open, whereby the signal S indicates "stop." When the car or train W passes out of the track section C-D, current will be supplied 115 to the rails of this section and the position of pole-changer P will be such that motor M is energized in such direction that centrifuge A (Fig. 2) is operated; contact 18-19 will then be closed so that signal S will 120 change to the "caution" indication. As the 125

car or train passes out of the section in advance of section C—D, pole-changer P will be reversed, whereupon the direction of rotation of motor M will be reversed, so that 5 centrifuge B (Fig. 2) will be operated; contact 20—21 will then be closed so that signal S will indicate "proceed."

Assuming that the relay comprises only the parts thus far referred to, it will be 10 observed that when the motor M is operating one or the other of the centrifuges, so that the signal S indicates "caution" or "proceed", and a train enters section C—D so that the motor M is stopped, the centrifuge 15 which was being operated will continue to spin for a considerable period of time until its momentum is absorbed by friction. The result is that the contact controlled by this centrifuge will remain closed 20 for a considerable period of time, so that after the train enters the section a considerable period of time will elapse before the signal will change to "stop". To avoid this sluggish action, I provide braking devices 25 for the centrifuges, which devices I will now describe.

Referring again to Fig. 2, fixed to the spindle 12 of centrifuge A is a disk 50 of electro-conductive non-magnetizable material, such as aluminum, which rotates 30 between the poles of a fixed U-shaped magnetizable core 51. This core is provided with a winding 52^a, and it is also provided with shading bands 53 so arranged that when 35 the winding is energized a torque is exerted on disk 50 tending to rotate the disk in the direction opposite to that in which it is rotated by the motor M. It will be clear, therefore, that when centrifuge A is rotating 40 and the winding 52^a is energized, a braking effect will be produced tending to bring the centrifuge to rest.

Centrifuge B is provided with a similar braking device, having a winding 52^b, the 45 shading bands being likewise so arranged that when the device is energized it exerts a torque on the centrifuge opposite to the direction in which the centrifuge is rotated by the motor.

50 For the control of the braking devices, I provide an auxiliary relay device E comprising a field core 57, a winding 35 thereon, a Z-armature 58, and a contact 36 controlled by this armature. The contact 36 is closed when the auxiliary device is de- 55 energized, and open when it is energized. The winding 35 of the auxiliary relay device E is included in series with the track winding 5 of the motor M (see Fig. 1) so that this device is energized or not accord- 60 ing as the track winding 5 is energized or not.

Further in control of the braking devices are two contacts 37—38 and 39—40 (see Fig. 65 1), operated by centrifuges A and B, re-

spectively. These contacts I will term "brake-controlling" contacts, to distinguish them from the other contacts which may be termed "signal-controlling" contacts. Each brake-controlling contact is open when its 70 centrifuge is at rest, and closed when it is rotating, but each brake-controlling contact is so arranged that as the centrifuge slows down this contact remains closed until after the signal-controlling contact operated by 75 the same centrifuge has opened. This is indicated diagrammatically in Fig. 1 by showing the openings of the brake-controlling contacts smaller than those of the signal-controlling contacts. 80

The energizing winding of each braking device is controlled by contact 36 of the auxiliary relay device E and also by the brake controlling contact operated by the corresponding centrifuge. Referring to Fig. 1, 85 the circuit for winding 52^a of the braking device for centrifuge A is from the secondary of transformer 31, through wires 41 and 54, contact 36, wire 55, winding 52^a, contact 37—38 wires 56 and 45 to transformer 90 31. The circuit for winding 52^b is similar except that it includes contact 39—40 instead of contact 37—38.

The operation of the braking devices is as follows: 95

I will assume that section C—D and the section in advance thereof are unoccupied, so that motor M is rotating in such direction that centrifuge B is operating whereby signal S indicates "proceed". The auxiliary relay device E is now energized so that the circuits for the braking devices are open at contact 36 and both of these devices are therefore deenergized. If now a car or train enters block section C—D, the auxiliary 100 relay device E will be deenergized so that its contact 36 will become closed. The braking device for centrifuge B, therefore, becomes energized and so exerts a torque tending to bring this centrifuge to rest. As the centrifuge slows down, contact 20—21 opens, thus causing the signal S to change to the stop indication; subsequently upon further slowing down of the centrifuge B, contact 105 39—40 opens, thus deenergizing the braking device so that while the centrifuge is at rest or below a predetermined speed this device consumes no current. Upon subsequent energization of motor winding 5, the auxiliary relay device E is simultaneously energized opening contact 36, so that even after one or the other of the brake controlling contacts becomes closed the corresponding 110 braking device is deenergized, and, consequently does not impede the operation of the 115 centrifuge. 120

If, while the section C—D is unoccupied, the section in advance is occupied so that centrifuge A is operating, then when a train enters section C—D the operation will be ex- 130

actly the same as before, the braking device for centrifuge A then being energized to quickly bring the speed of this centrifuge down below the point at which its signal controlling contact 18-19 opens.

Referring to Fig. 2, the armature 58 of the auxiliary relay device E is preferably provided with weighted arms 59 to render this relay slow in closing its armature contact 36. The purpose of this is to prevent momentary closing of this contact while pole-changer P (Fig. 1) is reversing. I thus avoid momentary energization of the braking devices while the auxiliary relay device E is momentarily deenergized, due to reversal of pole-changer P.

Although I have herein shown and described only one form of railway signaling system embodying my invention, it is understood that various changes and modifications may be made therein within the scope of the appended claims without departing from the spirit and scope of my invention.

Having thus described my invention, what I claim is:

1. A railway signaling system comprising a track section; a source of alternating signaling current reversibly connected with the rails of said section; a relay comprising a motor having a winding receiving energy from the rails of said section and rotatable in one direction or the other according as said source is connected with the rails in one direction or the other, two speed responsive devices one or the other of which is operated according as the motor rotates in one direc-

tion or the other, and contacts controlled by said speed responsive devices; and signaling means controlled by said relay contacts.

2. A railway signaling system comprising a track section; a source of alternating signaling current reversibly connected with the rails of said section; a relay comprising a motor having a winding receiving energy from the rails of said section and rotatable in one direction or the other according as said source is connected with the rails in one direction or the other, two centrifuges one or the other of which is operated according as the motor rotates in one direction or the other, brake-controlling contacts governed by said centrifuges, an auxiliary relay device associated with the circuit for said motor winding so as to be energized or not according as said motor winding is energized or not, braking means for each centrifuge controlled by said contacts and by said auxiliary relay device and operating when the contact controlled by the corresponding centrifuge is closed and the auxiliary relay device is deenergized, a signal controlling contact governed by each centrifuge and arranged to open before the brake-controlling contact of the same centrifuge opens when the motor is deenergized; and signaling means controlled by said signal-controlling contact.

In testimony whereof I affix my signature in presence of two witnesses.

ELMER R. COE.
